UNITED STATES PATENT OFFICE.

CHARLES LATTA, OF ST. LOUIS, MISSOURI.

GAS-ENGINE.

1,173,815.

Specification of Letters Patent. Patented Feb. 29, 1916.

Application filed March 25, 1914. Serial No. 827,123.

To all whom it may concern:

Be it known that I, CHARLES LATTA, a citizen of the United States, residing in the city of St. Louis and State of Missouri, have 5 invented a new and useful Gas-Engine, of which the following is a specification.

This invention relates to gas engines of the type including working pistons, and pumps for delivering gas to the piston cylinders, and consists more particularly of improvements in the valve mechanism by which the supply of gas is controlled in passing from the carburetor to the opening parts of the engine.

10 An object of the invention is to produce an improved engine of the type mentioned embodying a crank shaft driven by the pistons, and a rotary valve disk mounted on and driven by the crank shaft, with provision whereby the disk will control the flow 15 of gas to the pump devices and to the working piston cylinders.

Another object is to improve the construction of gas engines embodying working pistons and pump pistons connected to the same crank shaft, by generally re-arranging and re-organizing the construction and arrangement of the parts so that the greatest strain and force in the operation of the engine will be received upon the parts of 20 maximum strength.

Other objects will be made apparent by the following description of the invention, reference being made to the accompanying 25 drawings in which—

Figure 1 is a view, partially in elevation and partially in section, of an engine assembled and re-organized in accordance with the principles of my invention, and embodying 30 my improved valve mechanism. Fig. 2 is a sectional view of the engine cylinders, illustrating the arrangement of the passages from the valve mechanism to the cylinders of the working and pump pistons. Fig. 3 35 is a vertical sectional view of the engine illustrating the arrangement of the cranks on the crank shaft. Fig. 4 is a front side elevation of the valve mechanism case, the crank shaft which extends through said case 40 being in section. Fig. 5 is a view of the disk valve, the front part of the valve case being removed, and illustrating the valve in position against the inner or rear part of the 45 valve case. Fig. 6 is a view illustrating the interior construction of the inner or rear part 55 of the valve case. Fig. 7 is a view illustrating the exterior surface of the inner part of the valve case. Fig. 8 is a sectional view approximately on the line 8—8 of Fig. 4. Fig. 9 is an irregular sectional view substantially 60 along the line 9—9 of Fig. 4.

The cylinders are included within an engine case 1 which is rigidly secured to the upper part of a crank shaft case 2. The crank shaft case is provided on its opposite 65 ends with very substantial bearings 3, and is also provided with an intermediate bearing 4 in alinement with the end bearings 3. A crank shaft 5 is journaled in the bearings 3 and 4 and, in the embodiment shown, is 70 provided with two working piston cranks 6, and with two cranks 7 for the pump pistons 6, and with two cranks 7 for the pump pistons 75.

The cylinders 8 for the working pistons 9 are at the opposite ends of the casting 1 75 nearest the substantial bearings 3, so that the greatest force and strain in the operation of the engine, including the impact of the explosion of the gas in the cylinders 8, will be received upon the bearings, thus 80 contributing toward maximum strength and durability. The pistons 9 are connected to the cranks 6 by piston rods 10, so that the crank shaft 5 will be driven by operation of the pistons. In the embodiment illustrated 85 there are two working pistons 9, but it is obvious that the number of working pistons employed may be varied without departure from the spirit of the invention. For each of the working pistons there is a pump piston 11, the latter being mounted in suitable 90 cylinders 12 intermediate of the working pistons. The pistons 11 are connected with the cranks 7 by piston rods 13. The various cranks are suitably arranged so that 95 each pump piston 11 operates in advance of the corresponding working piston. Thus, a suitable arrangement consists in arranging the pump piston cranks 6, ninety degrees in advance of the corresponding working cranks. A water jacket space is formed intermediate of the casting 1 and the various cylinders inclosed therein for the circulation of the cooling water. On an extended portion of the crank shaft the valve 100 mechanism which constitutes an important 105

feature of the present invention is mounted. The valve mechanism includes a plate in the form of a disk 14 mounted upon the shaft 5. Keys 15 are seated in grooves in 5 the shaft 5 and in notches in the disk valve 14, so that said valve will be driven with the shaft 5. The valve is mounted in a suitable case consisting of a front or outer part 16 and a rear or inner part 17. The part 17 10 of the valve case is rigidly secured to some stationary part of the engine and is provided with a central opening through which the shaft 5 extends. The part 16 is also provided with a central opening through 15 which the shaft 5 extends, and is attached to the part 17 by means of a suitable number of bolts. In the embodiment shown the part 17 of the valve case is provided with a chamber in which the valve 14 is received, and the part 16 of the valve case 20 fits closely against the outer surface of the valve, thus closing the valve case and securing the valve in position therein. I utilize the single disk valve mounted upon and 25 driven by the crank shaft of the engine for controlling the supply of gas from the carburetor to the pumps and from the pumps to the working piston cylinders.

It will be understood that the pumps 30 operate to draw the gas from the carburetor through the valve into the pump cylinders 12, and operate further to force the gas from the pump cylinders through the valve into the working piston cylinders, the single 35 disk valve controlling the gas. The gas from the carburetor enters the valve case through a passage 18 which opens into divergent passages 19 and 20 which are for the purpose of supplying gas to the two 40 pump cylinders, respectively. It will be observed that the passage 19 is nearer the periphery of the disk 14 than is the passage 20. The passage 19 delivers gas to a suitable passage leading to the nearest pump 45 cylinder 12, whereas the passage 20 delivers gas to a passage leading to a more distant pump cylinder, the supply of the gas to both pump cylinders being controlled by the disk valve 14. The valve 14 is provided 50 with a passage 21 (Fig. 5) which is concentric with respect to the arcuate passage 19; and said valve is provided with another passage 22 which is concentric with the arcuate passage 20.

55 The inner or rear part 17 of the valve case is provided with a passage 23 which is concentric with the axis of the valve disk 14. The passage 23 matches the passage 19 from the point *a* to the point *b* (Fig. 6), 60 that is, through the length of the passage 19 there is a corresponding passage 23 on the opposite side of the valve disk. For a distance from the point *a* a web 24 separates the further extension of the passage

23 from the valve disk. The extent of the 65 web 24 is somewhat in excess of the length of the passage 21 through the valve disk, so that said passage 21 will be out of communication with the passage 23 during movement of said passage 21 from the part 23^a 70 of the passage 23 to the main part of said passage 23. After the passage 21 has moved from communication with the part 23^a of the passage 23, to the side of the web 24, the further movement of the valve disk moves 75 the passage 21 from the web 24 into communication with the main part of said passage 23, as will be apparent by reference to Figs. 5 and 6. The extended portion of the passage 23, for convenience to distinguish 80 said extended portion from the main portion of said passage, is indicated by 23^a. The passage 23 has an outlet 25 into a passage 26 leading to the nearest pump cylinder 12. 85

From the foregoing it is obvious that during movement of the passage 21 from the point *a* to the point *b* (Fig. 6), the passage 19 will be in communication with the passage 23 through said passage 21. Since the 90 length of the passage 19 is only slightly less than semi-annular, it is obvious that the supply of gas is in communication with the pump cylinder during approximately each entire downward stroke of the pump piston. 95 Thus, during each downward movement of the pump piston 11 gas from the carburetor is drawn into the pump cylinder 12 through the passage 19 and thence through the valve passage 21 into the passage 23 and thence 100 into the passage 26 into the pump cylinder. After the passage 21 through the valve disk is closed by passing beyond the ends of the passages 19 and 23, to cut off the supply of gas to the pump cylinder, communication is 105 effected between the pump cylinder and the adjacent working piston cylinder, so that the gas which had been drawn into the pump cylinder will be forced or pumped into the working piston cylinder by the upward movement of the pump piston. Separated from the passage 19 a passage 27 is formed 110 in the front or outer part 16 of the valve case, opposite from the extended part 23^a of the passage 23, so that when the valve 14 has moved the passage 21 around to the said passage 27 communication is effected from the pump cylinder to said passage 27. This 115 communication is effected during the upward movement of the pump piston so that the gas which had been drawn into the pump cylinder will be forced therefrom through the passage 26 and through the communication formed therewith by the part 23^a of the passage 23 opening through the passage 21 into the passage 27. A passage 28 leads 120 from the passage 27 to the piston cylinder 8 with which the pump now being described 125

coöperates, so that the gas will be forced from the pump cylinder into the coöperating working piston cylinder. This operation by which the gas is forced into the 5 working piston cylinder occurs during the upward stroke of the working piston 9, after the cylinder has been flushed to remove the products of the previous explosion, and after the piston has closed the exhaust outlet from 10 the cylinder. At the proper time after the passage 21 has moved beyond the passages 23^a and 27 the explosion is effected by the usual spark plug 29^b. This operation is repeated during each revolution of the crank 15 shaft.

The rear or inner part 17 of the valve case is provided with a passage 29 which is similar in function to the passage 23, and is provided with an extended part 29^a. The passages 29 and 29^a coöperate with the passage 22 to effect communication between the supply of gas from the carburetor and the other working piston cylinder in the same manner that communication is effected with one of 25 the working piston cylinders through the passages 23, 23^a and 21. The passage 29 communicates with its proper pump cylinder through a passage 30 in the valve case and a passage 31 leading from the passage 30 to 30 the pump cylinder. The communication is open and the supply of gas is drawn into the pump cylinder during the downward movement of the piston 12 in said pump cylinder, and during movement of the passage 35 22 from the point *c* to the point *d*, that is, while the passage 22 is in communication with the passage 29 in advance of the web 32 by which the passage 22 is closed while passing from the passage 29^a to the passage 40 29. Communication from the pump cylinder to the working piston cylinder is effected when the passage 22 communicates with the passage 29^a, at which time the passage 22 also communicates with a passage 33 in 45 the front or outer part 16 of the valve case. A passage 34 conducts the gas from the passage 33 to the working piston cylinder, so that the operation in these respects is similar to the operation hereinbefore described 50 in respect to one of the pumps and working pistons. The explosion is effected after the passage 22 moves from the passage 29^a and is closed by the web 32. After the passage 22 is carried beyond the web 32 into communication with the passages 29 gas is again drawn into the pump cylinder until the passage 22 moves beyond the closed end of the 55 passage 29. This operation of admitting gas into the pump cylinder and ejecting the gas from the pump cylinder into the working piston cylinder and effecting an explosion is repeated at each revolution of the valve disk.

In engines of this character there is more or less vibration of the mechanism, includ-

ing the crank shaft, due to the explosions of the gas in the cylinders. In order to prevent the transmission of this vibration directly to the valve disk, so that the valve disk may conform in its vibratory actions in movement of the case in which it is 65 70 75 in closed. The two case members are provided with chambers 35 to permit slight axial vibration of the crank shaft and the keys 15, with respect to the valve and the two members of the valve case. Thus a considerable amount of the vibration is absorbed or lost without affecting the valve case and the valve.

The working piston cylinders are flushed after each explosion by air forcing the products of explosion out through suitable flushing 80 85 86 passages 36.

The preferred embodiment of my invention illustrated includes the rotary valve mounted on an integral portion of the crank 85 shaft, and revolving at the same speed as the crank shaft revolves. It is obvious that my invention is not limited in its essential particulars to this arrangement, but that there may be various modifications and alterations in the construction and arrangement of the parts without departure from the spirit and scope of the invention.

I do not limit myself to the specific features and arrangement illustrated and described, but contemplate the use of any suitable or preferred equivalent constructions, to be determined by preference, or by the environments in which the engine may be used.

What I claim and desire to secure by Letters Patent of the United States is:

1. An engine, comprising a cylinder, a working piston mounted in said cylinder, a pump cylinder at the side of and parallel with said first-named cylinder, a crank shaft 105 driven by said piston, a valve case including outer and inner walls through which said crank shaft extends, a passage for admitting gas into said case, a separate passage from said case to said pump cylinder, a separate passage from said case to said working piston cylinder, a single valve member on said shaft within said case, and means whereby said valve member will control the admission of gas into said case, the passage 110 of the gas from said case to said pump cylinder, and the passage of the gas from said pump cylinder to said working piston cylinder through said case, substantially as described.

2. An engine, comprising a plurality of parallel working piston cylinders, a piston operating in each of said cylinders, a separate pump cylinder at the side of and parallel with each of said piston cylinders, a 115 120 125 crank shaft driven by said pistons, a case having outer and inner walls through which said crank shaft extends, separate passages

for admitting gas to said pump cylinders, respectively, separate passages for admitting gas to said piston cylinders, respectively, a valve disk mounted on said crank shaft between the walls of said case through which said crank shaft extends, and means whereby said valve disk will control the admission of gas to all of said pump cylinders through the separate passages leading thereto, and from said pump cylinders to all of said working piston cylinders through the separate passages leading to said piston cylinders, substantially as described.

3. An engine, comprising working piston cylinders, pistons mounted in said cylinders, a crank shaft driven by said pistons, a separate pump for each of said cylinders driven by said crank shaft, a case comprising inner and outer walls through which said shaft extends, a separate passage from said case to each of said pumps, a separate passage from said case to each of said cylinders, a valve mounted on said shaft within said case between the inner and outer walls thereof, means for driving said valve by said shaft, and means whereby said valve will control the admission of gas to all of said pumps through the said passages leading thereto, and from said case to all of said cylinders through the said passages leading to said cylinders, substantially as described.

4. In an engine, the combination with a working piston cylinder, a piston mounted in said cylinder, a crank shaft case, a crank shaft journaled in said case and driven by said piston, and a pump device for forcing gas into said cylinder, of outer and inner case walls outside of said crank shaft case through which said crank shaft extends, a passage for admitting gas into said case through one of said walls, a separate passage through one of said walls to said pump device, a separate passage through one of said walls to said cylinder, all of said passages being wholly outside of said crank shaft case, a rotary valve slidably keyed on said crank shaft between said case walls, and means whereby said valve will control the passage of gas into said passages, respectively.

5. In an engine, the combination with a number of working piston cylinders, working pistons mounted in said cylinders, a pump device for each of said cylinders, and a crank shaft driven by said pistons, of a case having outer and inner walls through which said crank shaft extends, a passage from said case to each of said pump devices, a passage from said case to each of said cylinders, a passage for admitting gas into said case, and a valve disk mounted on and rotating with said crank shaft between said outer and inner walls of said case and provided with passages for controlling the ad-

mission of gas to said pump devices, and from said case to said cylinders, respectively, substantially as described.

6. In an engine, the combination of a series of working piston cylinders, a working piston in each of said cylinders, a pump device for each of said cylinders, a crank shaft case, bearings in said case, a crank shaft journaled in said bearings and driven by said pistons, a valve case wall through which said crank shaft extends, a second valve case wall through which said crank shaft extends secured to said first-named wall, said two walls forming a valve case, passages from said valve case to said pump devices, respectively, passages from said valve case to said cylinders, respectively, a passage for admitting gas into said case, a valve mounted on said crank shaft between said walls of said case, passages in said valve effecting intermittent communication between said gas-admission passage and the passages to said pump devices, respectively, and other passages in said valve effecting intermittent communication between the passages to said pump devices and the passages to said cylinders, respectively, substantially as described.

7. In an engine, the combination of a piston cylinder, a piston mounted in said cylinder, a crank shaft driven by said piston, a valve case wall through which said shaft extends, a second valve case wall through which said shaft extends, a valve through which said shaft extends mounted between said walls, a passage opening through one of said walls for delivering gas through said valve, a passage from one of said walls to said cylinder, both of said passages being controlled by said valve, a key for driving said valve from said shaft, and means preventing the transmission of the vibration of said crank shaft to said valve.

8. In an engine, a piston cylinder, a piston mounted in said cylinder, a crank shaft driven by said piston, a valve case wall through which said shaft extends, a second valve case wall through which said shaft extends, means holding said two walls together, a valve disk through which said shaft extends mounted between said walls, a key for driving said valve disk with said shaft and permitting lateral movement of said disk with respect to said shaft, a pump device and passages controlled by said valve disk for controlling the admission of gas to said pump device and to said cylinder through said valve, substantially as described.

9. In an engine, the combination of a piston cylinder, a piston mounted in said cylinder, a crank shaft driven by said piston, a valve case wall through which said shaft extends, a second valve case wall

through which said shaft extends, means holding said walls together, a valve mounted between said walls and driven by said shaft, a passage controlled by said valve for admitting gas to said cylinder, and means preventing the transmission of the vibration of said crank shaft to said valve, substantially as described.

In witness whereof, I have signed this specification in the presence of two sub- 10 scribing witnesses.

CHARLES LATTA.
